UNITED STATES PATENT OFFICE.

WILLIAM R. JEAVONS, OF CLEVELAND, OHIO.

DESIGN FOR A DRUM-BASE FOR STOVES.

45,008.

Specification for Design.

Patented Dec. 9, 1913.

Application filed August 12, 1911. Serial No. 643,807. Term of patent 7 years.

To all whom it may concern:

Be it known that I, WILLIAM R. JEAVONS, a citizen of the United States, residing at Cleveland, in the county of Cuyahoga and State of Ohio, have invented a new, original, and ornamental Design for Drum-Bases for Stoves, of which the following is a specification, reference being had to the accompanying drawing, forming part thereof, wherein

the figure represents in elevation a stove having a drum-base exhibiting my new design.

I claim:—

The ornamental design for a drum base for stoves, as shown.

WILLIAM R. JEAVONS.

Witnesses:

J. B. HULL,
BRENNAN B. WEST.
